CLAIM

The ornamental design for a robotic workstation, as shown and described.

DESCRIPTION

FIG. 1 is a right side view of a robotic workstation showing my new design;

FIG. 2 is a top view thereof;

FIG. 3 is a bottom view thereof;

FIG. 4 is a front view thereof;

FIG. 5 is a left side view thereof;

FIG. 6 is a rear view thereof; and,

FIG. 7 is a front perspective view thereof.
